UNITED STATES PATENT OFFICE.

WILLIAM H. FULPER, OF FLEMINGTON, NEW JERSEY.

DESIGN FOR A COVER FOR CONTAINERS.

Application filed March 9, 1921. Serial No. 450,968. Term of patent 3½ years.

To all whom it may concern:

Be it known that I, WILLIAM H. FULPER, a citizen of the United States of America, and resident of Flemington, county of Hunterdon, and State of New Jersey, have invented a certain new, original, and ornamental Design for a Cover for Containers, of which the following is a specification, reference being had to the accompanying drawing, forming part thereof.

In the drawing, the figure is an elevation of a cover for containers embodying my invention.

I claim:—

The ornamental design for a cover for containers as shown.

WILLIAM H. FULPER.
